UNITED STATES PATENT OFFICE.

GEORGE E. MOLYNEUX, OF BAYONNE, NEW JERSEY, ASSIGNOR TO THE SINGER MANUFACTURING COMPANY, A CORPORATION OF NEW JERSEY.

SPEED CONTROLLING AND ARRESTING MECHANISM FOR SEWING-MACHINES.

1,236,739.

Specification of Letters Patent. Patented Aug. 14, 1917.

Application filed July 14, 1911. Serial No. 638,473.

To all whom it may concern:

Be it known that I, GEORGE E. MOLYNEUX, a citizen of the United States, residing at Bayonne, in the county of Hudson and State 5 of New Jersey, have invented certain new and useful Improvements in Speed Controlling and Arresting Mechanism for Sewing-Machines, of which the following is a specification, reference being had therein to the 10 accompanying drawings.

This invention relates to improvements in a speed-controlling and arresting mechanism for sewing machines, and has for its object to provide automatic means for determining the speed of the machine when it is acted upon to discontinue its operation, and means for automatically determining the position of rest of the needle with respect to its limit of movement.

20 The details of the improvements and their operation will more fully appear hereinafter.

In the accompanying drawings illustrating the invention, in the several figures of 25 which like parts are similarly designated, Figure 1 is a sectional view in front side elevation, representing a feed-up-the-arm sewing machine embodying the present improvements. Fig. 2 is a plan view of the 30 sewing machine with the base of the bracket-arm in section, the overhanging member removed and the cover-plate for the work-support omitted. Figs. 3, 4, 5 and 6 are details, in perspective, of the improved 35 mechanism. Fig. 7 is a front end view of the cylinder-bed or work-supporting horn and one form of commonly employed power transmitter for effecting and discontinuing the transmission of power. Fig. 8 is a rear 40 side elevation of the transmitter shown in Fig. 7.

For a proper understanding of the application of the present invention, it is herein shown and described as applied to the sewing machine construction represented by my 45 United States Patent No. 1,111,167, September 22, 1914, but as the present invention is applicable to sewing machine constructions generally, only such reference will be 50 made to the details in construction of the stitch-forming and cloth-feeding mechanisms as is deemed important to an understanding of the invention.

The frame of the machine is shown 55 formed with a hollow base 1, standard 2,

overhanging bracket-arm 3 provided with a head 4, and cylinder-bed or work-supporting horn 5 having its flange 6 secured by screws, as 7, to said base. The standard is provided at its rear end with a bearing boss 60 8 containing the bushing 9 in which is journaled the rear end of the main-shaft 10 fitted within a bearing member 11 formed upon the rearward end of the work-supporting horn 5, the reduced forward portion 12 65 of said main-shaft being journaled in a bearing boss 13.

The bracket-arm is provided at its rearward end with a bearing boss 14 in which is journaled the rearward end of the needle- 70 actuating rock-shaft 15 whose forward end is fitted to and passes through the bearing member 16 in the head 4 where it is provided with the usual crank-arm 17 carrying a pin 18 connected by means of a pitman 19 with 75 a lateral pin formed integral with the collar 20 fixed upon the needle-bar 21 carrying the eye-pointed needles, as 22. Upon the rearward end of the rock-shaft 15 is fixed a lateral crank-arm 23 which carries 80 a stud 24 embraced by the upper end of a pitman 25 whose lower end embraces a crank 26 formed in the main-shaft 10 and adapted to communicate, through the described connecting mechanism, reciprocating movements 85 to the needle-bar and needles.

The needle-actuating rock-shaft 15 has fixed thereon, at the side of the bearing boss 14 opposite the crank-arm 23, a second lateral crank-arm 27 carrying a screw-stud 28 90 (shown in dotted lines only, Fig. 1) embraced by the upper end of the pitman rod 29 whose lower end embraces a screw-stud 30 intermediate the ends of a vibrating lever 31 having one end journaled upon 95 the fixed fulcrum-pin 32 mounted in an inwardly projecting boss 33 formed upon the standard 2. The outer end of the lever 31 is provided with a suitable screw-pin (not shown) connected by means of a link 34 100 with a similar pin (not shown) carried by a crank-arm 35 fixed upon the rearward end of the looper rock-shaft 36, whereby the latter is caused to transmit, through its attached looper-carrier 37, loop-seizing and 105 shedding movements to the looper 38.

The sidewise or needle-avoiding movements are imparted to the looper 38 by means of an actuating cam 39 secured upon the forward end of the main-shaft extension 110

12 by means of a suitable set-screw (not shown) and provided with a peripheral cam-groove 41. Journaled in the bearing member 42, beneath and parallel with the looper rock-shaft 36, is a reciprocating rod 43 formed on one side with a suitable spline (not shown) to prevent its turning while permitting its free endwise movements, and having adjustably secured to its rearward end by means of set-screws, as 44, a collar 45 with a rearwardly extending arm 46 carrying a roller-stud 47 entering the groove 41 of the cam 39, from which it derives its reciprocatory movements. In the reduced forward end portion 49 of the rod 43 is secured the shank 50 of a ball-stud whose spherical portion 51 is fitted within suitably socketed independent sections, as 52, of a receiving block which is in turn fitted within the segmental raceway 53 of the looper-carrier 37, whereby the latter is permitted to oscillate freely with its supporting shaft.

The feed-eccentric 54 is embraced by the strap 55 of an eccentric-rod 56 whose opposite end embraces a ball-eccentric upon the rearwardly extending arm 57 of a plural-armed rocker mounted upon the fixed fulcrum-stud 58 carried by the lug 59 extending inwardly from the wall of the base 1, and having a second laterally extending arm 60 carrying a ball-stud embraced by a strap 61 at the rearward end of the feed-bar 62 extending longitudinally through the work-supporting horn 5 above the rock-shaft 36 and formed near its forward end with a reduced cylindrical portion 63, to which latter is secured the slide-block 64 channeled in its upper side to receive the shank 65 of the serrated feed-dog 66 secured therein by means of the fastening screw 67.

To the reduced intermediate portion 63 of the feed-bar 62 is slidingly fitted a tilting bearing or fulcrum-block 68 formed with lateral bosses, as 69, which are entered by fulcrum-screws, as 70, passing through the opposite members of a yoke 71 embracing said fulcrum-block and formed at the upper end of an upright lifting bar or post 72, the latter apertured at its lower end to form a strap 73 to embrace the feed-lifting eccentric 74 fixed on the reduced forward portion 12 of the shaft 10 adjacent the cam-cylinder 39. The post 72 has also a clearance aperture intermediate its ends through which passes the looper rock-shaft 36.

As will be observed, the longitudinal reciprocating movements of the feed-bar for effecting the advance of the work up the arm of the machine toward the standard 2 is produced through its described connections with the feed-actuating eccentric 54, while the rising and falling movements of the feed-dog are produced by the feed-lifting eccentric 74 through the post 72 and tilting bearing 68 swiveled therein.

75 represents the presser-foot whose shank 76 is rigidly secured to the lower end of the presser-bar 77 journaled in suitable bearings in the head 4 of the bracket-arm, a cam-shaped lever 78 acting on a lug 79 to raise said presser-bar in opposition to the resiliency of the spring 80 to accommodate the manual manipulation of the fabric being acted on, and 81 represents the needle-thread tension.

Having described sufficient of the sewing machine stitch-forming and cloth-feeding mechanism for an understanding of the application of the present invention, there will now be described one form of well-understood means for operatively connecting the sewing machine main- or driving shaft with the source of power.

82 represents a power-transmitter bracket secured by screws, as 83, to the under side of the table 84 and provided at its lower end with a hub 85 into which is secured by screw 86 a non-rotating shaft 87 which extends to the right of said hub, as shown by dotted lines, Fig. 7, and upon which is mounted to 90 rotate the power-driven pulley 88, in practice connected by a suitable belt (not shown) with the source of power, and the machine driving pulley 89 connected by the belt 90 with the pulley 91 carried by the main-shaft 95 10. As is well understood, when the treadle 92 is rocked in the direction indicated by the arrow *t*, the connecting rod 93 moves the inclined surface 94 into contact with the shaft thimble 95 whose inner end contacts with the surface 96 of the pulley 88, causing the latter to be forced into driving contact with the leather 97 carried by the pulley 89. The lever 98, having the inclined surface 94, is secured by screw 99 on the rock-shaft 100 105 mounted to oscillate in a hub 101 forming a part of the bracket 82, the opposite end of said rock-shaft having secured to it by screw 102 an arm 103 carrying a brake 104 and provided with a lug 105, and between said lug and a lug 106, forming a part of the bracket 82, is confined a spring 107 which normally acts to hold said brake in contact with the rim 108 of the pulley 89. 108' represents a guard-bracket secured by a screw 115 110 to the shaft 87.

The foregoing is descriptive of a preferred form of well-understood construction of power-transmitting mechanism, but it is to be understood that many other forms common to commercial use might be substituted, as, for instance, such constructions as employ a loose and tight pulley mounted on the main-shaft of the sewing machine, as represented by the United States Patent to 125 A. D. Pentz, No. 231,189, dated August 17, 1880; and further, if a sewing machine equipped with the present invention was controlled to operate at a comparatively low speed (1000 or less stitches per minute), 130

the employment of a power-transmitter equipped with a brake device could be dispensed with in favor of the ordinary loose and tight pulley and shifting belt.

5 There will now be described the mechanism comprising the subject of the invention.

To the base 1 is secured by screws, as 109, a stop-disk 110 concentric with the shaft 10, 10 said disk being provided with a curvilinear recess 111 in which are arranged springs 112 and 113 the adjacent ends of which are arranged on opposite sides of and in contact with the guide-block 114 to which is secured 15 by screws as 123' the resistance member 115, and upon the periphery of said disk is secured by screws, as 116, a stop-bracket 117. 118 represents a brake-disk mounted upon the shaft 10 to move in the direction of the 20 length of the latter and secured to rotate with said shaft by suitable splines (not shown) secured in suitable guideways (not shown) formed in said shaft and coacting with the respective grooves 119 and 120 25 formed in the hub 121 of said brake-disk, which latter carries a stop member 122 secured by suitable screws, as 123.

Adjustably secured on the shaft 10 by suitable screws, as 124, is a spider-collar 125 30 provided with lugs, as 126, each forked to embrace the respective bellcrank-levers, as 127, provided with arms, as 128, carrying spherical weights, as 129, and pivoted to the respective lugs by means of suitable screws, 35 as 130, a spring 131 interposed between the fixed collar 125 and the brake-disk 118 normally serving to hold the stop member 122 within the peripheral opening 132 formed in the disk 110 and extending from the wall 40 133 to the incline 134, for a purpose later to be explained.

135 represents an L-shaped lever pivotally mounted in a notched standard 136 secured in the base 1, one arm of said lever being 45 connected by an expanding connection 137 with the treadle 92. The other arm of said lever is forked to engage a grooved collar 138 loosely mounted on a stud-bolt 139 secured in the side wall of said base, said 50 stud-bolt being provided at its inner end with a flange 140 against which steps one end of a spring 141 which serves to resiliently hold the said collar against the inner wall of said base. 142 represents a shifting 55 lever pivoted upon screw 143 threaded into a bracket 144 extending inward from the base 1 and provided at one end with a roller-stud 145 which enters the groove in the collar 138, the opposite end of said shifting lever being provided with a stud 146 which coacts with a cam-lever 147 pivoted upon a screw 148 secured in the disk 110. 60 The inner end 149 of said cam-lever enters a groove 150 formed in the shifting collar 65 151 loosely mounted on the main-shaft 10

and located between the inner wall of the base 1 and the brake-disk 118 carrying the stop-member 122.

The free ends of the arms 128' are provided with inclines, as 152, which, when the 70 machine is in operation, coact with the inclined surface 153, through the centrifugal action of the weights 129, to hold the rotating stop member 122 out of engagement with the resistance member 115, as will now 75 be explained.

Supposing the machine to be at rest as illustrated in Fig. 2, the operator rocks the treadle 92 in the direction indicated by the arrow *t* which first acts on the expanding 80 connection 137 to oscillate the L-shaped lever 135 and, through the connections 138, 142, 147 and 151, moves the brake-disk 118, in opposition to the resiliency of the spring 131, away from the stop-disk 110 a distance 85 sufficient to disengage the members 115 and 122, or in position to permit the shaft 10 to be rotated, the spring 154 permitting the treadle to be brought in contact with the nut 155 and, through the connection 93, causing 90 the incline 94 to operatively connect the pulley 88 with the friction leather 97 carried by the machine driving pulley 89, thus first releasing the main-shaft from the control of the stop mechanism, followed by the transmission of power from the supply to said 95 main-shaft.

In manually adjusting the brake-disk 118 away from the stop-disk 110, the lever 135 is limited in its movement by the adjustment 100 of the winged screw 156 to move said brake-disk only sufficient to allow the stop member 122 in its rotations to clear the resistance member 115, thus adjusting the arms 128' of the bellcrank-lever 127 with respect to 105 the incline 153 of the brake-disk 118 so that the corners, as 157, of said arms are carried only slightly down the incline 153 of said disk 118, in which relationship they are held by the centrifugal action of the weights 129 110 until the transmission of power is discontinued, when, if the brake 104 is employed, the speed of the machine will commence to slacken almost instantly, which results in 115 said weights releasing the corners 157 from engagement with the incline 153, and as soon as the straight surfaces, as 158, of said arms are brought in alinement with the straight surface 159 of the brake-disk 118 the spring 131 forces the stop member 122 into 120 engagement with the resistance member 115, which latter acts to cushion said stop member to the extent of its contacting with the stop bracket 117, when the action of the springs 111 and 112 will register the member 122 in its normal or shaft registering position.

Should the speed of the main-shaft exceed that necessary to cause the weights to 125 register the corners 157 with respect to the 130

incline 153 as previously pointed out, the centrifugal action of said weights will cause the inclines 152 to travel down the incline 153 as shown in Fig. 1, when the brake-disk 5 118 will be adjusted beyond the limit of movement of the collar 151, thus releasing the shaft 10 from all frictional engagement with the elements comprising the speed-controlling and arresting members carried 10 by said shaft.

Having thus set forth the nature of the invention, what I claim herein is:—

15 A speed controlling and arresting mechanism including a main-shaft, a brake-disk 15 slidably mounted on said shaft for rotation therewith and provided with a rim, said rim having an inclined wall, a collar fixedly secured upon said shaft and provided with bellcrank-levers the outer free ends of each 20 of which carries a centrifugally controlled

weight, means for moving said brake-disk in one direction, the oppositely arranged free ends of said bellcrank-levers being provided with an inclined wall engaging the inclined wall of said slideable brake-disk and 25 coöoperating with said means for moving the brake-disk in one direction whereby the sliding movement of said brake-disk is controlled and a fixed brake member provided with a stop for arresting the rotation of 30 said collar and shaft in a predetermined position.

In testimony whereof, I have signed my name to this specification, in the presence of two subscribing witnesses.

GEORGE E. MOLYNEUX.
